UNITED STATES PATENT OFFICE.

OSCAR B. WELKER, OF MIDDLETOWN, CONNECTICUT, ASSIGNOR TO THE WELKER-HOOPS MANUFACTURING COMPANY, OF MIDDLETOWN, CONNECTICUT, A CORPORATION OF CONNECTICUT.

CAP FOR CONTAINERS.

Application filed June 8, 1923. Serial No. 644,141.

To all whom it may concern:

Be it known that I, OSCAR B. WELKER, a citizen of the United States, and a resident of Middletown, in the county of Middlesex and State of Connecticut, have invented new and Improved Caps for Containers, of which the following is a specification.

My invention relates to that class of devices that are commonly used in connection with various types of containers, the contents of which have to be replenished at more or less frequent intervals, and an object of my invention, among others, is to provide a cover for these containers that shall have a maximum efficiency both as to tightness to prevent the contents of said containers or similar devices from splashing or leaking out through said cover, and as to means whereby the mouth of a container may be opened or closed and the cover may also be locked by a very simple and easy operation of a handle. A further object of the invention is to provide a cover that can be easily attached to the opening of a container in common use without the aid of tools to replace the ordinary removable cover supplied therewith, and so constructed that it will not necessitate its removal from the container when it is desired to uncover said opening.

One form of device embodying my invention and in the construction and use of which the objects herein set out, as well as others, may be attained, is illustrated in the accompanying drawings, in which—

Figure 1 is a view in vertical section through a cover embodying my invention, the operating handle being shown in end view.

Figure 2 is a similar view of the device taken at right angles to the point of view of Figure 1, but with the lock plate also shown in full.

Figure 3 is a plan view of the device showing the cover in unlocked and opened position.

It is a well known fact, especially in connection with covers which are removably attached to containers such as are used for automobile gasoline tanks, radiators and the like, that require the frequent removal of the cover for the purpose of filling the container, that it is often forgotten to replace the cover, which fact being unnoticed at

the time results in said cover being consequently lost. With my device as hereinafter described this cannot happen.

In the accompanying drawings the numeral 7 denotes a ring shaped supporting member having a screw threaded portion 8 which provides a suitable means by which my device can be secured to the threaded flange 9, that is commonly used in connection with containers of the character herein mentioned. The numeral 10 denotes a section of one of these containers.

The supporting member 7 has formed thereon ears 11 to which is hinged, by a pin 12, an ear 13 secured to a cover plate 14. This cover plate has a flange 15 which overhangs the edge of the supporting member 7 and also serves to contain within the cover plate a washer 16. An operating handle 17 has an operating stud 18 projecting through the cover plate and on which a plate 19 is mounted.

The end of this stud is squared and riveted as at 20 to secure the plate 19 thereto and against turning movement thereon. This plate is formed to provide a locking flange 21 at its periphery, each half of this flange being separated from the other half by notches 22 shaped to form locking cams as clearly shown in the drawings.

The supporting member 7 is provided with locking lugs 23 which serve to engage the locking flange 21 to lock the cover in its closed position.

It can be readily seen that when the cover is closed the locking lugs 23 will pass through the notches 22 and that by a simple turn of the operating handle 17 the plate 19 is partially rotated, causing the locking flange 21 to come into contact with the lugs 23 and by a continuation of the turning motion on the handle 17 the cam flange 22 is passed under the locking lugs and thus the cover is pulled down tightly into engagement with the supporting member 7. The recess in the ear 13 being slightly larger than the pin 12 sufficient play will be allowed to permit the cover plate to properly seat.

As the plate 19 herein shown is formed of spring material, it will tend to resiliently keep the cover tightly closed and also prevent it from binding or becoming loose.

- In connection with covers for containers it is desirable to provide a vent for the interior of the container. This I accomplish with my improved device by means of a 5 vent opening 24 in the cover plate and into the air space within the supporting member 7 and over the plate 19, said plate thus serving, in addition to its other functions, hereinbefore described, as a baffle plate.
- 10 It will thus be seen that by causing the plate 19 to serve as a baffle plate any leakage of the contents due to splashing through the opening 24 is prevented since the plate will obstruct direct passage through the 15 vent hole. This baffle plate being made smaller than the opening in the supporting member 7, a sufficient air space is provided around the said plate to permit the vent to properly function.
- 20 My improved device may be attached to the mouth of a container in the same manner as the ordinary screw cap therefor and after such attachment will provide a cover that cannot become misplaced or lost.

While a hinge is shown herein as a means 25 for securing the cover to the support in a manner to permit the opening in the support to be uncovered, yet I contemplate other means for attaching the cover to the support to attain this same result, and I do 30 not therefore confine my invention to the means shown for securing this result.

I claim—

A closure comprising a supporting member, a cover plate, a stud rotatable in the 35 cover plate, an apertured boss depending from the cover plate through which the stud passes, a combined baffle and locking plate of disk formation interlocked with the lower end of the stud and so retained by the 40 boss on the cover, said baffle and locking plate having diametrically opposite cut-away portions with the remaining divided edge of the plate being of cam formation and diametrically opposite lugs on the supporting member cooperating with the cam formations at the edge of the plate. 45

OSCAR B. WELKER.
